UNITED STATES PATENT OFFICE.

EDGAR LANGLEY RANDALL, OF SOUTH HAMPSTEAD, LONDON, ENGLAND, ASSIGNOR OF
THREE-FOURTHS TO OLIVER PRESCOTT MACFARLANE, OF LONDON, ENGLAND.

VAPOR-BURNER FOR STOVES.

1,195,160.

Specification of Letters Patent. Patented Aug. 15, 1916.

Application filed February 17, 1915. Serial No. 8,824.

To all whom it may concern:

Be it known that I, EDGAR LANGLEY RANDALL, a subject of the King of Great Britain, residing at 11 Lithos road, South 5 Hampstead, N. W., in the county of London, England, have invented certain new and useful Improvements in Vapor-Burners for Stoves, of which the following is a specification.

10 This invention relates to oil-vapor burners and stoves, and relates more particularly to burners such as used for stoves or for heating purposes generally.

The main object of the invention is to 15 provide a burner or stove of extremely simple construction, which shall be efficient and economical in working and capable of using any suitable liquid fuel, such as ordinary kerosene or paraffin oil, or even alcohol, or 20 methylated spirit.

According to the invention, the liquid fuel oil is vaporized in a straight tube lying transversely above the burner, said oil being fed in through a suitable filter, under air-pressure in the ordinary way. The vapor 25 from this tube is discharged into one end of a bent or U-shaped mixing tube, the other end of which carries the burner. The whole 30 is surrounded by a sheet metal wall or casing.

The action is started by first heating the device with a charge of methylated spirit as usual. To this end a small spirit-cup or trough may be fitted to the casing, and 35 adapted to be moved into position for heating the vaporizer tube, and then be moved out of the way to allow the flame of the resulting kerosene or other vapor to impinge on the said tube when once the stove or 40 burner is alight.

The burner or stove may be used for any ordinary heating purpose, and also for heating objects of any kind or material for which gas or spirit flames can be used. It 45 may for instance be employed to heat radiating bodies, tubes or caps for converting the heat of the clear blue flame into radiant heat, and for this purpose the stove may if desired be fitted with silica caps or mantles.

50 Figure 1 is a vertical section of an example of a heating burner or stove according to the invention. Fig. 2 is a plan thereof. Fig. 3 is a detail plan view of the removable spirit cup or trough, Fig. 4 being a section 55 thereof on the line 4-4 of Fig. 3.

a is the horizontal vaporizing tube, which is secured by screwing, by silver solder or otherwise, to a filter-tube or chamber *c*, which is connected by a screw-joint with the supply pipe from the oil reservoir. The 60 oil is forced into the vaporizer *a* from a reservoir in which it is kept under air-pressure, in the manner usual in lamps or burners of this kind.

The filter-chamber *c* contains a wire-65 gauze roll, cartridge or filling, through which the oil passes on its way to the vaporizer. Owing to the temperature acquired by the gauze or filling, the filter tube or chamber *c* although only short, serves also as a 70 heater tube to assist in vaporizing as well as atomizing the incoming oil, this being an important feature. From this short filter tube *c* the oil is passed into the straight vaporizing tube *a* which is secured in a small 75 plate *a'* screwed on to the shell or casing *j* hereinafter mentioned, or it might be screwed directly to the said casing. The tube *a* lies diametrically across the stove, centrally over the burner, and terminates in 80 a small brass block *f* having at its lower part, a nipple of any suitable kind provided with the orifice for the vapor jet, which is directed downwardly at right angles to the tube *a*. At a short distance below such orifice is an air-inlet *g* in the side of the injector or mixing tube *g*, into which the vapor jet is discharged from the nipple, 85 said jet drawing in by suction the necessary quantity of air for proper combustion with 90 a clear flame. *g* is an ordinary regulator ring for closing the inlet *g* more or less as required to give the best mixture. This regulator is turned around by the small 95 handle or finger piece *g* to uncover the hole *g* more or less as required. At the other or 100 U-shaped extremity of the tube *g* is the burner head, lying centrally directly under the vaporizing tube *a*, as above indicated. This burner head may comprise a cup-shaped piece *h* forming as it were an annular or trough-like flange concentric with and silver-soldered around the outlet mouth of the mixing tube or injector *g*. In this 105 cup-shaped piece is supported a small removable baffle-plate *h* situated directly above the mouth of the injector tube and carried by rests or feet *h*. The mixing tube *g* is held in position by a union nut *f* on the piece *h*, and by loosening this nut the 110

said tube g and the parts h^2 h^3 can be easily removed.

The whole is surrounded by, or inclosed within, a suitable metal casing, jacket or cylinder j (say of sheet iron) to protect it from drafts, this cylinder being mounted on bent iron legs or supports k , the hook-shaped tops k^1 of which form rests for a kettle or other article to stand on.

10 It will be seen that the upright flame plays directly on the straight tube a , and easily produces the desired heating effect. The preliminary heating to start the action, can be effected very quickly by means of the small removable sliding trough l (Figs. 3 and 4), which can be pushed through an aperture in the side of the casing j , and will serve to contain the necessary charge of methylated spirit for heating up the straight tube a sufficiently to cause the vaporization of the incoming oil. After this preliminary heating the action proceeds as follows:—The paraffin oil forced in through the filter chamber c is 20 vaporized in the hot tube and forms at or near g^2 a combustible mixture with the air which it sucks into the mixing tube g . This mixture issues from the annular space around the edge of the plate h^3 and burns 25 freely and evenly thereat, without any gauze being actually necessary around such annular space. The trough l used in starting to heat the tube a , is of course drawn out at this time. The flame from h^2 can then 30 play freely upward and keeps the tube a properly heated so insuring a continuance of the effective vaporizing of the incoming oil.

35 The burner or stove may be used for any ordinary heating purposes, and for heating objects of any kind or material for which gas or spirit flames can be used. It may for instance be employed to heat radiating bodies, tubes or caps for converting the heat 40 of the clear blue flame into radiant heat,

Copies of this patent may be obtained for five cents each, by addressing the "Commissioner of Patents, Washington, D. C."

and for this purpose the stove may if desired be fitted with silica caps or mantles.

I claim:—

1. In a vapor burner for paraffin, alcohol or other liquid fuel, the combination of a 50 straight vaporizing tube, a metal casing open at its top and bottom, the upper part of which supports the said vaporizing tube, a plain vertical mixing tube having a U-shaped lower extremity, and a burner sup- 55 ported at the bottom of the casing by the upwardly-turned lower end of such mixing tube, substantially as described.

2. In a vapor burner for paraffin, alcohol or other liquid fuel, the combination of 60 a straight vaporizing tube, a filter device arranged to be highly heated and placed directly in line therewith at one end thereof, a downwardly-directed nipple at the other end thereof, a mixing tube having a 65 U-shaped curved lower extremity, a regulator for the air-inlets of the mixing tube, and a metal casing distinct from the mixing tube and completely open at the top and bottom, substantially as described. 70

3. In a vapor burner for paraffin, alcohol or other liquid fuel, the combination of an outer casing, a plain straight tube extending across the top of said casing, a filter adapted to be highly heated at one end of 75 said tube and contained in one end of said tube, a vapor nipple at the other end of said tube, an air and vapor mixing tube having a U-shaped lower extremity, such tube being supported by and depending from the nipple, and a burner carried at the bottom of 80 the casing directly on the upturned end of the U-shaped part of the mixing tube, substantially as described. 85

In testimony whereof I affix my signature in presence of two witnesses.

EDGAR LANGLEY RANDALL.
